UNITED STATES PATENT OFFICE.

CHARLES S. BURTON, OF OAK PARK, ILLINOIS, ASSIGNOR TO MELVILLE CLARK, OF CHICAGO, ILLINOIS.

TRACKER-MOUTHPIECE AND ACCENTING DEVICE FOR AUTOMATIC MUSIC-PLAYING INSTRUMENTS.

964,389.

Specification of Letters Patent. Patented July 12, 1910.

Application filed January 8, 1908. Serial No. 409,809.

To all whom it may concern:

Be it known that I, CHARLES S. BURTON, a citizen of the United States, residing at Oak Park, in the county of Cook and State 5 of Illinois, have invented new and useful Improvements in Tracker-Mouthpieces and Accenting Devices for Automatic Music-Playing Instruments, of which the following is a specification, reference being had to the 10 drawings, forming a part thereof.

The purpose of this invention is to provide an improved tracker mouth-piece adapted for accomplishing several purposes in connection with automatic music-playing instruments, prominent among which is accenting or specializing selected notes of the music, as, for example, those constituting the melody. The device as characterized in this invention is also adapted to produce 20 sostenuto effect in automatic music instrument playing; and it is also adapted to remedy the defect consisting in the inaccurate registrations of the controlling sheet with the tracker mouth due to the contraction and 25 expansion of the paper constituting such controlling sheets.

In the drawings:—Figure 1 is an elevation showing a tracker mouthpiece and perforated controller sheet coöperating there- 30 with having features which constitute this invention, the controller sheet being in part broken away, and the tracker mouthpiece being also in part broken away. Fig. 2 is a front elevation or edge view of a modified 35 tracker mouth-piece shown diagrammatically in relation to the mouth-piece, and controller sheet of Fig. 1. Fig. 3 is a view similar to Fig. 1 showing a modification in the controller sheet. Fig. 4 is a detail section of 40 the tracker board at the line 4—4 on Fig. 1.

The characteristic feature of this invention, so far as it relates to the tracker, consists in the construction of the mouth piece, A, or apertured edge element of the tracker 45 board or duct board, B. This tracker mouth piece has the mouths for the tracker ducts consisting of slots, a, which extend obliquely with respect to the direction of travel of the paper, as for example at about an angle of 50 45 degrees thereto, each slot occupying a portion of the length of the tracker board equal to the full distance between centers of the slots, so that a series of parallel lines be-

ing drawn in the direction of travel of the controller sheet through the extreme right-hand points of the respective slots, each such line will touch the extreme left-hand point of the slot next adjacent to the one through whose extreme right-hand point it is drawn. These slots may be made in a strip of metal 60 constituting the mouth piece, A, as described, which may be mounted upon the edge of the tracker board or duct board, B, in which the ducts, b, may be formed in the usual manner opening in a straight line, each duct 65 under or behind one of the oblique slots, a, of the mouth piece, so that the uncovering of the slot, a, of the mouth piece at any point in its length will admit air to the tracker duct, b, for controlling the pneumatic action 70 of the instrument. The controller sheet, C, has the apertures for the notes which are not to be emphasized or specialized not wider, preferably, than about half the distance between centers of the slots, a, and cut in lines 75 situated with respect to the means for gag- 80 ing the paper in its path over the tracker board, so that the leading ends of such slots will reach and register with the oblique slot, a, at the farther ends of the latter.

It will be seen that if any particular aperture as c¹ is laterally displaced from the above described position—to the right as the slots are shown sloped in the drawing—it will reach and register with the slot, a, 85 at the nearer end of the latter, and that the air will thereby be admitted to the tracker duct through such laterally displaced perforation as much sooner than the air is admitted to the other slots for the 90 same chord by the registration of their remote ends with the corresponding apertures as the length of time required by the paper for moving between the two regis- 95 tering positions over the belt or zone of said oblique tracker mouths. At any convenient points in the tracker board, preferably at the ends, supplemental mouth piece slots, a^x, are provided, and the controller sheet may have supplemental apertures, c^x. 100 These supplemental apertures, c^x, will be situated so as to reach the supplemental mouth piece slots, a^x, at the nearer end of the latter,—that is, substantially at the same time that the apertures, c¹, reach their 105 respective tracker mouth slots.

It may be understood that the ducts from the tracker mouth, a^x , lead to pneumatically controlled devices for operating tone or stroke modifying devices of the instrument, 5 and that when the supplemental apertures, c^x , register with the supplemental tracker duct mouths, a^x , these tone or stroke modifying devices will be operated, and that all notes which are struck at that instant will 10 be subject to this modification, which, for the purpose of emphasizing the melody, will be an intensification. Only the note or notes in a chord which are to be specialized will be offset or have their leading ends offset so 15 as to reach the nearer end of the oblique tracker mouth slots, and these notes only will be subject to the modification of tone, the aperture, c^x , passing by the tracker mouth slot, a^x , and putting out of service 20 the tone or stroke modifying devices by the time the remaining apertures, c , pertaining to the same chord reach the farther ends of their respective tracker mouth slots. In Fig. 1, I have shown the exceptional or 25 specialized apertures c^1 in the perforated sheet offset bodily laterally to reach the nearer end of the oblique tracker mouth slots, but the same effect will be produced by merely jutting off the leading end of the 30 slot an equal amount laterally. Such construction is shown in Fig. 3, and is the preferred form at least because it is the form in which paper can be more easily prepared without special perforating machines, the 35 apertures c^x being first cut in their normal position and then having the lateral offset, c^y , formed at their leading end.

It will be obvious that when the tone modifying devices are of such character that 40 the modification must continue throughout the entire chord after it is once affected, the unemphasized notes must be first struck before the tone modifying devices are operated, and that in such case the specialized 45 apertures for the melody and the supplemental apertures for operating the tone modifying devices must be offset in such direction as to register with the more remote instead of the nearer ends of their respective 50 oblique tracker mouth slots, and the normal or regular position of the slots for playing the unspecialized notes will therefore be such as to cause them to register with the nearer instead of the more remote 55 ends of their respective tracker mouth slots. Since the difference in this respect will be in the construction of the instrument as to the nature of the tone modifying devices it is preferable that the difference should be 60 altogether in the instrument, and that no difference should be required in the controlling sheet, and therefore for such instruments the tracker mouth piece will have its slots cut sloping in the opposite direction, 65 as shown in Fig. 2. The same perforated

sheets in that case will operate with the desired effect upon instruments having either type of tone modifying devices.

The tracker mouth piece above described, having the mouths consisting of oblique 70 slots, is adapted to serve two additional purposes with ordinarily cut note sheets. The first of these purposes is to remedy the defect due to contraction and expansion of the paper constituting the controlling sheet. 75 By reason of the fact that there is no waste portion of the length of the tracker board,—that is, that at no point in its length can a perforation of the paper cross the board without registering at some point in its 80 path with a tracker duct mouth,—and that not more than half of the unit distance,—that is, the distance between centers of the tracker mouths,—is required for the width of the controller sheet apertures, a contraction and expansion of the paper sufficient to displace the most affected apertures from three-fourths to seven-eighths of one full diameter or width of the unit may occur 85 without preventing them from operating 90 properly, (with the exception hereafter mentioned) because the slot thus displaced, laps on the corner of the proper tracker duct mouth adequately to cause action there-through, laps too little on the opposite corner of the next duct mouth to cause action through the latter. The exception noted is that if the paper is at normal or average condition as to expansion and contraction, gaged so that the perforations cross the 100 tracker duct mouths at the middle points of the latter, a change in the width of the paper which causes the apertures to cross the mouths at one side or the other of the middle point will delay or hasten the sounding of the note, but so slightly that the effect is not ordinarily perceptible; and it has only the effect of rendering the sound of the music somewhat more human, because such slight inaccuracies as it causes are not 110 greater than those which occur in hand playing, and which to some extent distinguish hand playing from automatic playing. The second additional purpose served by the oblique tracker duct mouths is that two notes 115 following each other in the music and which it is desired to run together for sostenuto effect may be thus played by cutting the aperture for the second of the two notes in the same manner as shown for an accented 120 note,—that is, so that it will reach the nearer end of the slot and will thus begin to sound before the preceding note has left the farther end of its slot. The apertures, c^6 and c^7 , 125 illustrate the use of this expedient for sostenuto effect, the aperture, c^6 , being normal or regular in its formation and position, and the aperture, c^7 , for the note which is to follow, having its leading end offset to reach the nearer end of its tracker mouth slot be- 130

fore the terminal end of the aperture, c^6 , has left its tracker mouth slot. It will be understood that each of these two additional uses of the oblique-mouthed tracked board described requires suitably perforated note sheets, and when such board is used for the purpose first described,—viz., selection of melody notes, so much of the range of the slots longitudinally of the board due to their obliquity as is utilized for this purpose is not available at the same time, for compensating for expansion and contraction, but the same board is adapted to serve each of these purposes separately.

15 I claim:

1. In an automatic music-playing instrument, a tracker mouth piece having duct mouths in the form of slots trending obliquely across the range of the mouth piece.
2. In an automatic music-playing instrument, a tracker mouth piece having the tracker duct mouths in the form of slots, each of which trends obliquely across the range and occupies a portion lengthwise thereof equal to the distance between centers of the slots.
3. In an automatic music-playing instrument, in combination, a tracker board having its tracker mouths in the form of slots trending obliquely across the tracker range, and having a supplemental duct and mouth therefor designed for communication with tone or stroke modifying devices; a perforated note sheet having its apertures for the notes which are not to be specialized situated for registering with the tracker duct mouths at one end thereof respectively, and having apertures for notes which are to be

specialized cut with their leading ends in position for registration with the other end of their respective tracker duct mouths, such note sheet having also a supplemental aperture for registering with the mouth of the supplemental duct of the tracker out of time with the apertures for unspecialized notes and in time corresponding with the registration of the leading end of the apertures for specialized notes.

4. In an automatic music-playing instrument, in combination with a tracker board having its duct mouths in the form of slots trending obliquely across the tracker range, and having a supplemental duct and mouth designed for controlling tone modifying devices, a perforated note sheet having apertures for the notes which are not to be specialized situated in position for registering their leading ends with the same ends of the oblique tracker mouths, and having apertures for the notes which are to be specialized also cut as to the body of the aperture in similar relation to the tracker duct mouths, but having the leading end offset laterally for registering with the other end of the oblique tracker mouth, and having a supplemental aperture situated for coincident registration with the mouth of the supplemental duct.

In testimony whereof, I have hereunto set my hand, in the presence of two witnesses, at Chicago, Illinois, this 3d day of July, 1907.

CHARLES S. BURTON.
